ICE CUBE TRAY

Albert S. Haislip, Fredericksburg, Va.

Application July 27, 1933, Serial No. 682,498

7 Claims. (Cl. 62—108.5)

My invention relates to an improved pan or tray of the slideable drawer type used in current types of electric refrigeration machines for convenient freezing and molding of ice cubes.

It is a matter of common knowledge that the present day type of metal or aluminum tray is generally in the form of a longitudinally elongated flat bottom pan having a removable internal cellular partitioning unit for the formation of ice cubes. This pan or tray is placed slidably in an appropriate coil equipped rack or holder having a flat supporting bottom against which the flat bottom of the pan rests in intimate contact to promote expeditious cube freezing results.

While this arrangement promotes expeditious ice cube formation it is obvious that the bottom of the tray adheres or sticks to its resting or supporting surface. Frequently the ice adhesion is such as to make it difficult to slide or pull the tray out for dumping of the cubes. At the present time it is a makeshift practice to accomplish this result by employing any instrument such as a knife or screw driver which may be handy at the time to pry the tray loose. Manifestly, this results in damage to the parts which is ruinous as well as decidedly undesirable.

I have therefore discovered a need for the provision of a mechanical lever actuated thrust device of an extensible and retractable type to be mounted on one end of the tray in a convenient position to permit the lever to be expeditiously grasped to actuate the device to lift the pan, break the ice bond, and to permit the pan to be thereafter easily slid out for use.

Other features and advantages will become more readily apparent from the following description and drawing.

Figure 1 is a front elevational view of a pair of superposed trays located in the rack or holder (shown in dotted lines) illustrating the end elevational appearance of each of the trays.

Figure 2 is a fragmentary view in section and elevation illustrating the supplemental pan lifting and release means incorporated in the frontal portion of the tray and disclosing its preferred construction and arrangement.

Figure 3 is a fragmentary sectional view taken approximately on the plane of the line 3—3 of Figure 2 looking outwardly, that is in the direction of the arrows.

As before implied the invention is primarily adapted for use on a conventional aluminum tray or pan, the same being denoted by the numeral 4. It is of customary design having the usual flat bot-

tom 5. In the present instance the front end wall thereof 6 is formed with a drawn depending flange or apron 7 of appropriate proportion and configuration, the same being integrally joined to the front wall of the tray through the medium of an appropriately curved web 8. In its upper portion and centrally between the opposite ends this depending flange is provided with a vertically elongated slot 9. On the inner face of the flange is a part which may be generally designated as a fixture or bracket 10 and this preferably comprises attaching plates 11 of suitable shape riveted or otherwise secured in place as indicated at 12. It is provided with upper and lower vertically aligned and apertured guide lugs 13 and 14 respectively to accommodate a reciprocatory lifting and releasing pin or bolt 15. On its upper end the pin has a depressible head 16. Surrounding the upper projecting or headed end of the pin is an expansible coil spring 17 bearing at its lower end against the upper guide lug 13. Thus the spring 17 functions as a return spring for automatically returning the pin to an elevated position and to retain the lower end thereof normally flush with or above the bottom 5 of the tray.

Manually actuated means is provided for depressing the pin against the tension of the spring and this means is in the form of a handle or lever which is generally referred to by the numeral 18. The lever is equipped with an appropriate hooked hand grip 19 and further formed with a cam element 20. This cam element projects inwardly through the slot and is pivotally mounted on a cotter pin or the like 21 supported in spaced parallel ears 22 forming a part of the aforesaid attaching bracket. Incidentally in its broadest conception this attaching bracket is referred to as "guide means" for the spring returned slideable release pin. It is to be observed that the lever 18 is located on the outer side of the flange 7 and the cam 20 protrudes inwardly through the slot in a position to bear upon the head 16 as shown in the drawing. The numeral 23 merely designates an extension which may be described as a slot closure or filler. In other words when the lever is in its normal closed position as shown in Figure 2 this extension projects into the slot and closes the upper end portion of the slot. The extension however does not interfere with the lifting of the lever in the direction of the arrow when the lever is brought into play.

It is evident that by grasping the hooked portion 19 of the lever 18 and lifting it in the direction of the arrow this swings the cam 20 down in an arc and inasmuch as the cam is in contact with

the head 16 the pin 15 is forced down against the tension of the coiled spring 17. This projects the pin down beyond the lowermost guide 14 so that it engages the supporting surface of the tray holder, thus lifting the pan and breaking the ice seal to facilitate withdrawal of the pan.

It is obvious that with this arrangement the spring normally maintains the pin in a retracted position and its lower end is flush with the bottom of the tray. Thus the presence of the device on the tray does not interfere with the smooth insertion thereof into the holding rack. If, however, the tray becomes stuck by adhesion of the frost it can be easily lifted and loosened through the instrumentality of the device here provided.

A device of this type is believed to be ingenious and of such simplicity and practicability to justify its endorsement as an innovation in this particular line of endeavor. It is feasible and practical and will undoubtedly fulfill the requirements of the invention in a highly practical and satisfactory manner. It is easy to operate and conveniently located and in no way interferes with the normal functioning of the tray.

A careful consideration of the foregoing description in conjunction with the illustrative drawing will enable the reader to obtain a clear understanding of the purpose, features and advantages, the explicit construction, and the invention as hereinafter claimed.

It is to be understood that minor changes in shape, size, relative proportions, and materials may be resorted to in practice without departing from the spirit of the invention or the scope of the invention as now claimed.

Having thus described my invention, what I claim as new is:

1. An ice cube tray, a bracket having guide members on the front wall of said tray, a thrust pin mounted for vertical sliding movement in said guide members, spring return means for said pin surrounding the pin, said return means serving to retain the lower end of the pin retracted to a substantially flush position with respect to the bottom tray, and manually actuated means carried by said tray and cooperable with the upper end of the pin for actuating said pin, said means being in the form of a pivoted lever and having a cam element engageable with said pin.

2. An ice cube tray provided on its front wall with a vertical guide, a headed pin slidably mounted in said guide, a coil spring surrounding the upper end portion of the pin beneath the head and bearing on said guide to normally retract and retain the pin in an out of the way position, a cam mounted for oscillation on the tray above and in contact with the head of said pin.

3. An ice cube tray provided on its front wall with a vertical guide, a headed pin slidably mounted in said guide, a coil spring surrounding the upper end portion of the pin beneath the head and bearing on said guide to normally retract and retain the pin in an out of the way

position, a cam mounted for oscillation on the tray above and in contact with the head of said pin, and a handle attached to said cam to facilitate actuation of the cam and to further facilitate withdrawal of the tray after it is loosened.

4. In a structure of the class described, an ice cube tray provided on its front wall with a depending apron-like flange depending in spaced parallelism to the front wall of said tray, said flange being provided at a predetermined point with a vertically elongated slot, a guide equipped bracket mounted on the inner surfaces of said flange, a spring returned headed release pin slidably mounted in said bracket, the headed portion of said pin being located adjacent said slot, a lever pivotally supported on said flange and including a cam extending inwardly through the slot and engageable with the head of said pin.

5. In a structure of the class described, an ice cube tray having one end wall thereof formed with an integral flange depending in spaced parallelism to said one end wall, said flange being provided adjacent its upper portion with a vertically elongated slot, a bracket fastened to the inner surface of the flange and spaced from said end wall, said bracket being provided with upper and lower guide lugs and adjacent its upper end with apertured ears located in alignment with said slot, a pin slidably mounted in said lugs, said pin being provided on its upper end with a head, a return spring surrounding the headed end of the pin and bearing on the adjacent lug, a lever disposed on the outer side of said flange, the free end portion of said lever being formed into a finger hook, the opposite end portion thereof being provided with a cam extending inwardly through the slot and pivotally supported between said ears, said cam being located for depressible engagement with the head of the pin.

6. An ice bond breaking and cube tray lifting device comprising a thrust pin adapted for vertical disposition and reciprocation, guide and attaching means for securing said pin to said tray, a manually controlled pin depressing lever separate and independent of said pin, said lever being adapted for disposition at right angles to the pin and liftable upwardly and provided with a cam engageable with the complementary end of said pin order to depress the pin.

7. In a structure of the class described, a guide bracket adapted for attachment to an ice cube tray of the class described, a thrust producing plunger pin mounted for vertical sliding in said bracket, spring means associated with the bracket and pin for maintaining the pin in a normal retracted out of the way position, an actuating lever adapted to assume a position at approximate right angles to said pin, and cam coacting means between the inner end of said lever and upper end of said pin, whereby when said lever is grasped and pulled upwardly said pin is forced downwardly in the manner and for the purposes described.

ALBERT S. HAISLIP.
